SOFT SURFACE FLOOR COVERING

Gerald E. White, Albertson, N.Y., assignor to Congoleum
Industries, Inc., Kearny, N.J.

Filed Mar. 12, 1973, Ser. No. 340,309

Term of patent 14 years

Int. Cl. D6—04

U.S. Cl. D92—4

Fig. 1

Fig. 2

Fig. 3

Fig. 4

Fig. 5

FIG. 1 is a plan view of a soft surface floor covering embodying my new design, showing a regular repeating unit.

FIG. 2 is a cross-sectional view taken along line 2—2 of FIG. 1 and viewed in the direction of the arrows.

FIG. 3 is a view of a portion of FIG. 1.

FIG. 4 is a cross-sectional view taken along line 4—4 of FIG. 3 and viewed in the direction of the arrows.

FIG. 5 is a plan view of a soft surface floor covering embodying my new design, and showing a plurality of the regular repeating units shown in FIG. 1.

The back surface opposite to the surface shown in FIG. 1 is a conventional planar backing without ornamentation.

I claim:

The ornamental design for a soft surface floor covering, as shown and described.
